UNITED STATES PATENT OFFICE

171,438

MESSAGE RACK OR SIMILAR ARTICLE

Zenas A. Bump, Fresno, Calif.

Application February 24, 1953, Serial No. 23,750

Term of patent 14 years

(Cl. D80—11)

To all whom it may concern:

Be it known that I, Zenas A. Bump, a citizen of the United States, residing at 2694 Elm Avenue, Fresno, county of Fresno, and State of California, have invented a new, original, and ornamental Design for a Message Rack or Similar Article, of which the following is a specification, reference being had to the accompanying drawings, forming a part hereof.

Fig. 1 is a perspective view of a message rack or similar article showing my new design.

Fig. 2 is a top plan view thereof.

Fig. 3 is a side elevational view thereof.

Fig. 4 is an end elevational view thereof. The opposite side and the opposite end to that shown in Figs. 3 and 4 are identical in appearance to the side and end shown.

I claim:

The ornamental design for a message rack or similar article, as shown and described.

ZENAS A. BUMP.
